F. J. HULL.
SAND BLAST APPARATUS.
APPLICATION FILED APR. 30, 1912.

1,054,775.

Patented Mar. 4, 1913.

UNITED STATES PATENT OFFICE.

FOSTER J. HULL, OF BROOKLYN, NEW YORK, ASSIGNEE TO THOMAS W. PANGBORN COMPANY, OF JERSEY CITY, NEW JERSEY, A CORPORATION OF NEW YORK.

SAND-BLAST APPARATUS.

1,054,775.

Specification of Letters Patent.

Patented Mar. 4, 1913.

Application filed April 30, 1912. Serial No. 694,238.

To all whom it may concern:

Be it known that I, FOSTER J. HULL, a citizen of the United States, and a resident of Brooklyn, in the county of Kings and State of New York, have invented certain new and useful Improvements in Sand-Blast Apparatus, of which the following is a specification.

My invention relates to improvements in sand blast apparatus, and comprises an improved sand-container and improved sand-and-air mixing means, together with an improved valve controlling the delivery of the sand from the container.

The objects of my invention are to improve and simplify sand blast apparatus, to provide improved and effective means for regulating the action of such apparatus, and to so construct the sand-delivery valve of the apparatus that the portion thereof subject to material wear may be renewed readily.

I will now proceed to describe my invention with reference to the accompanying drawing and will then point out the novel features in claims.

In the drawings Figure 1 shows a central vertical section of the apparatus constructed in accordance with my invention. Fig. 2 shows a transverse section through the valve stem at the point of engagement thereof by the valve rod. Fig. 3 is a detail central vertical section, on a larger scale, of the valve at the bottom of the pressure tank, and associated parts; Fig. 4 is a detail side elevation of the latch mechanism for the handle 16, and Fig. 5 is a detail horizontal section of such latch mechanism.

In said drawing 1 designates a pressure tank adapted to contain sand or other abrasive material, and having an outlet at 2 for the sand, which outlet is guarded by a suitable screen 3. 4 designates an air tube extending downwardly through this container 1, and connected at the lower end to a valve-casing 5, within which is a hollow valve-spindle 6 provided in its side with a port 7 through which air under pressure may pass from the interior of valve body 5 into the bore 8 of the valve spindle. The tube 4 is connected at its upper end to a hollow bonnet 9 into which air under pressure is delivered by a suitable valved pipe 10, such air being taken from a compressed air tank 11 or other suitable source of sup-

ply. There is also a valved connection 12 from this pipe 10 to the upper portion of container 1. Beneath the discharge outlet 2 of container 1 there is a mixing chamber 13, to the outer end of which may be connected a hose 14 for carrying away the current of sand-laden air to the point of use.

Within the central air tube 4 of container 1 there is a rod 15, usually of square or other polygonal cross section, which rod is seated at its lower end in a socket of corresponding form in the top of the valve spindle 6, this rod 15 serving as means for rotating the valve spindle. Said rod 15 passes through a suitable stuffing box at the upper end of the bonnet 9 and is there provided with a handle 16 whereby said rod may be turned to effect rotation of the valve spindle 6. This handle 16 is provided with a spring-actuated latching dog 16^a engaging notches in a rack 9^b of the bonnet 9.

The valve bonnet 5 has at its lower end a flanged portion 17 in which is a discharge port 18 registering with discharge opening 2 of container 1; and within said flanged portion 17 of the valve bonnet there is a removable valve seat 19 secured to the flanged portion 17 by suitable means, as for example screws 20. This valve seat 19 has in it a port 21 which registers with the discharge opening 18 above mentioned.

The valve stem 6 carries a valve disk 22 keyed to the valve stem 6 by a key 22^a so as to be rotated thereby when the valve stem is turning, the purpose being to bring the valve opening 23 of the valve disk into more or less complete registry with the valve ports 21 and 18 thereabove, in order to vary the delivery of the sand, or to stop it altogether. Spring 24 within the valve bonnet 5 holds the valve disk 22 against the removable valve seat 19, this spring bearing against a shoulder of the valve bonnet and against a shoulder 25 provided on the valve spindle, the valve spindle having also a nut 26 bearing against the valve disk.

It will be seen that in operation the delivery of sand from the container 1 may be varied as desired by adjustment of the valve disk, or the delivery of the sand may be cut off altogether. Supposing this valve to be open to a greater or less extent, sand will pass from the interior of container 1 through the valve to the bore of the mixing chamber 13, where it will encounter air

under pressure passing downward through air tube 4 and hollow valve spindle 6, the air and sand thus mixed passing outward through the hose 14.

5. What I claim is:—

1. Sand blast apparatus comprising in combination a pressure tank adapted to contain granular abrasive material, and having a downwardly directed discharge opening at its bottom, an air pipe extending from the top of the tank downward into proximity to said discharge opening, a hollow valve casing secured to said air pipe, a movable valve member carried by said casing and movable transversely across said discharge opening, for regulating flow through said opening, said valve member having a downwardly directed port, means located within said air pipe and valve casing for operating said valve member, and means for supplying compressed air or other elastic fluid to the upper portion of said pressure tank and to said air pipe.
2. Sand blast apparatus comprising in combination a pressure tank adapted to contain granular abrasive material, and having a downwardly directed discharge opening at its bottom, an air pipe extending from the top of the tank downward into proximity to said discharge opening, a hollow valve casing secured to said air pipe and forming a downward extension thereof, and projecting through said discharge opening, there being discharge space around said valve casing, a movable valve member carried by said casing and movable transversely across such discharge opening, and regulating flow through said opening, said valve member having a downwardly directed port, means located within said air pipe and valve casing for operating said valve member, and means for supplying compressed air or other elastic fluid to the upper portion of said pressure tank and to said air pipe, said valve member provided with a passage for the flow of air from the interior of said valve casing into the space beneath the valve.

3. Sand blast apparatus comprising in combination a pressure tank adapted to contain granular abrasive material, and having a downwardly directed discharge opening at its bottom, an air pipe extending from the top of the tank downward into proximity to said discharge opening, a hollow valve casing secured to said air pipe and forming a downward extension thereof, and projecting through said discharge opening, there being discharge space around said valve casing, a movable valve member carried by said casing and movable transversely across such discharge opening, and regulating flow through said opening, said valve member having a downwardly directed port, means located within said air pipe and valve casing for operating said valve member, and means

for supplying compressed air or other elastic fluid to the upper portion of said pressure tank and to said air pipe, said valve member provided with a passage for the flow of air from the interior of said valve casing into the space beneath the valve, and a mixing chamber beneath said discharge outlet and valve and in which the abrasive material and air passing through said valve mix.

4. Sand blast apparatus comprising in combination a pressure tank adapted to contain granular abrasive material, and having a downwardly directed discharge opening at its lower end, a valve casing located in part within the tank and having a flanged and ported seat portion extending across such discharge opening, a ported valve disk rotatably mounted adjacent the seat portion, and means for rotating said disk.

5. Sand blast apparatus comprising in combination a pressure tank adapted to contain granular abrasive material, and having a downwardly directed discharge opening at its lower end, a valve casing passing through said opening and located in part within the tank and having a flanged and ported portion extending across such discharge opening, a correspondingly ported valve seat removably secured to such flanged portion, a valve disk rotatably mounted adjacent the surface of said seat, and means for rotating said valve disk.

6. Sand blast apparatus comprising in combination a pressure tank adapted to contain granular abrasive material, and having a downwardly directed discharge opening at its lower end, a valve casing located in part within the tank and having a flanged and ported seat portion extending across such discharge opening, a ported valve disk rotatably mounted adjacent the seat portion, and means for rotating said disk, and means for holding such valve disk against its seat.

7. Sand blast apparatus comprising in combination a pressure tank adapted to contain granular abrasive material, and having a downwardly directed discharge opening at its lower end, a hollow valve casing located in part within the tank and having a flanged and ported seat portion extending across such discharge opening, a ported valve disk rotatably mounted adjacent the seat portion, a valve spindle secured to said disk and located within said valve casing, a spring within the valve casing acting against such spindle and tending to hold said valve disk against its seat, and means engaging said spindle for rotating said valve disk.

8. Sand blast apparatus comprising in combination a pressure tank adapted to contain granular abrasive material, and having a downwardly directed discharge opening at its lower end, a hollow valve casing located in part within the tank and having a flanged

and ported seat portion extending across such discharge opening, a ported valve disk rotatably mounted adjacent the seat portion, a valve spindle secured to said disk and located within said valve casing, a spring within the valve casing acting against such spindle and tending to hold said valve disk against its seat, an air pipe connected to the valve casing and extending upwardly through said tank, means for supplying compressed air or other elastic fluid under pressure to said air pipe and to the upper

portion of said tank, said valve spindle being hollow and provided with a port connecting its bore with the interior of said valve casing, and means for rotating said valve disk.

In testimony whereof I have signed this specification in the presence of two subscribing witnesses.
